L. E. COOKE

SMOKER'S ARTICLE

Filed May 9, 1924

UNITED STATES PATENT OFFICE.

LEO E. COOKE, OF DENVER, COLORADO.

SMOKER'S ARTICLE.

Application filed May 9, 1924. Serial No. 712,017.

To all whom it may concern:

Be it known that I, LEO E. COOKE, a citizen of the United States of America, residing at Denver, in the county of Denver and 5 State of Colorado, have invented certain new and useful Improvements in Smokers' Articles, of which the following is a specification.

This invention relates to smokers' articles 10 and has for its principal object the provision of a device of this character which will conveniently and efficiently serve as an ash tray, a tobacco receptacle, a cigarette holder, a match holder, a humidor, and which will 15 provide convenient storage for boxed cigars and the like.

A further object of the invention is to provide individual receptacles for ashes, and discarded cigar or cigarette butts, which will 20 be practically smoke proof so as to prevent the smoke from discarded butts escaping into the room.

Other objects and advantages reside in the detail construction of the invention, 25 which result in simplicity, economy, and efficiency, and which will become more apparent from the following description.

In the following detailed description of the invention reference is had to the accompanying drawing which forms a part hereof. 30 Like numerals refer to like parts in all views of the drawing and throughout the description.

In the drawing:

Fig. 1 is a perspective view of the complete invention.

Fig. 2 is a horizontal cross-section taken on the line 2—2, Fig. 3.

Fig. 3 is a vertical cross-section taken on the line 3—3, Fig. 2.

Fig. 4 is a similar cross-section taken on the line 4—4, Fig. 2.

The invention comprises a stand, 10, carrying a cabinet, 11, which is provided with a 45 hinged door, 12. Supported on the stand 10, is a housing 13, which is illustrated as a hexagonal in shape but is not necessarily limited to such a shape. The housing 13 is provided with feet 14, arranged to fit into 50 openings 15 in the top of the stand 10 and hold it in place thereon.

Should it be desired to use the housing 13 independently of the stand, it may be readily lifted off, felt pads 16 being provided on the 55 legs 14 to prevent the marring of furniture upon which the container may be placed.

A metallic receptacle 17, shaped to conform to the shape of the housing 13, is fitted therewithin. The receptacle 17 contains a series of radial extending compartments 18 60 and 19 and a central cylindrical compartment 20. In each face of the housing 13, a hinged door 21 is provided, which is opened by means of a finger hold 22 and lies, when opened, upon a door rest 23. Certain of the doors 21 carry, secured to their interior faces, ash trays 24 and cigar rests 25, as illustrated in Fig. 4, other of the doors 21 carry on their interior faces V-shaped tobacco bins 26, as illustrated in Fig. 3.

In Fig. 4, the right hand door is shown as it would appear when in use, the left hand door being shown in the closed position. In Fig. 3, the left hand tobacco bin is shown in the open position, allowing ready access to the tobacco, and the right hand door is illustrated in the closed position, which affords complete protection for the tobacco.

It can readily be seen that any ashes or 80 other débris accumulated in the ash tray 24 will be deposited into the bottom of the compartment 18 when the door is closed. If desired, water may be placed in the compartment 18, as shown at 27, to extinguish the 85 discarded butts. The housing 13 is closed by means of a flanged cover 28, which fits snugly within the top of the housing 13 and against the top of the receptacle 17 and the separating partitions between the compartments 18 and 19, so as to prevent smoke 90 from a closed compartment escaping through the door of an open compartment.

The wall of the cylindrical compartment 20 projects upward through a round opening in the cover 28, as shown at 30, and the compartment is closed by means of an ornamental metal lid 29. In the compartment 20, partitions 31 are placed which divide it into three cells, a central one 38 in which a package of cigarettes 32 may be placed resting on a false bottom 33, and two sector shaped cells 34 which may be used to retain a box of matches 25 or in which matches 100 may be held in bulk.

Openings 36 may communicate between the compartments 19 and the interior of the cabinet 11, and serve to conduct moisture, either from a humidor in the cabinet 11 to the compartments 19 or from a sponge or 110 other moistening device, 37, in the compartments 19 to the cabinet 11. This arrange-

ment serves to keep both the tobacco in the bins 26 and in the cabinet 11 in moist condition.

- When it is desired to clean the receptacle, 5 all of the doors 21 are opened, the cover 28 removed, and the receptacle 17 is lifted out of the housing 13. This allows the ashes to be dumped from the compartments 18 without disturbing the tobacco in the bins 26.
- 10 If the lid 29 is kept in place, the matches and cigarettes in the compartment 20 will be prevented from falling out while the receptacle 17 is being inverted for dumping.

In Fig. 4 the housing 13 is shown detached from its stand and supported by the legs 14 on an exterior support.

While a specific form of the improvement has been described and illustrated herein, it is desired and understood that the same 20 may be varied, within the scope of the appended claims, without departing from the spirit of the invention.

Having thus described the invention, what I claim and desire secured by Letters 25 Patent is:—

1. A smoker's article comprising a housing; a container placed within said housing; a door hinged on said housing and a cigar holder and ash tray secured to said door and

arranged to deposit their contents into said 30 container as said door is closed.

2. A smoker's article comprising a container; a series of compartments within said container; a lid adapted to close said container and the compartments from each other; doors opening to said compartments; ash trays and cigar rests secured to the inner faces of said doors and arranged to deposit their contents into said compartments as said doors are closed. 40

3. A smoker's article comprising a container; a series of compartments within said container; a lid adapted to close said container and the compartments from each other; doors opening to said compartments; ash trays and cigar rests secured to the inner faces of certain of said doors and arranged to deposit their contents into certain of said compartments as the doors are closed and tobacco receptacles secured to other of 50 said doors and arranged to extend within other of said compartments when the doors are closed and beyond said container when said doors are open.

In testimony whereof, I affix my signature. 55

LEO E. COOKE.
